PAGE 4

fig. 4

Fig. 5

Figure 1 is a front perspective view of a lawnmower embodying our new design.

Figure 2 is a rear oblique view of said mower.

Figure 3 is a left side view of said mower.

Figure 4 is a top plan view of said mower.

Figure 5 is a front elevational view of said mower.

The characteristic features of the lawnmower reside in the portions shown in full lines.

We claim:

The ornamental design for a lawnmower, as shown and described.
